UNITED STATES PATENT OFFICE.

GEORGE E. MITTINGER, OF YOUNGSTOWN, OHIO.

BAND-ANCHOR FOR TANK-CARS.

1,254,525.

Specification of Letters Patent. Patented Jan. 22, 1918.

Application filed September 27, 1917. Serial No. 193,436.

To all whom it may concern:

Be it known that I, GEORGE E. MITTINGER, a citizen of the United States, residing in Youngstown, in the county of Mahoning and 5 State of Ohio, have invented certain new and useful Improvements in Band-Anchors for Tank-Cars, of which the following is a specification, reference being had therein to the accompanying drawing.

10 My invention relates to improvements in band anchors for tank cars.

The object of my invention is to provide a band anchor of this character in which the band is firmly held therein and can not be 15 disengaged therefrom by the slight loosening of the nuts carried by the ends of the band.

Another object of my invention is to provide a band anchor which can be rigidly secured to the under frame of the car and at 20 the same time providing a simple cheap and effective structure having certain details of structure and operation hereinafter more fully set forth.

25 In the accompanying drawings—

Figure 1 is a transverse sectional view of a tank car showing my invention applied thereto.

Fig. 2 is an enlarged vertical sectional 30 view of the anchor showing the connection with the under frame of the tank car.

Fig. 3 is a front plan of the anchor.

Fig. 4 is a rear plan of Fig. 3.

Referring now to the drawings, 1 represents the tank of the usual construction used 35 on tank cars and is supported by the cradle 2 which in turn is supported by the longitudinal supporting sills 3 and 4. These sills as shown are of the channel iron form and 0 are supported on any well known form of car construction and to which are secured the anchors all of which needs no further description.

5 My improved anchor consists of a rear plate 5 adapted to rest against the vertical wall 6 of the channel sill and has its upper end bent at an angle at 7 to correspond with the upper flange of the sill so that it will lie flat against the under face of the flange as 0 clearly shown in Fig. 2 of the drawings. The lower end of the rear plate 5 is bent outwardly as indicated at 8 and said outwardly or bent or extending portions 8 and 7 are connected by a hollow web 9 which has its 5 lower end gradually curved outwardly as in-

dicated at 10 and the lower end or wall 11 of the web is arranged at an angle of approximately 45 degrees to the rear plate. The web 9 as heretofore stated is hollowed from the rear face and said hollow portion 12 terminating some distance above the lower end forming the solid portion 13.

The solid lower portion 13 of the web 9 is provided with an opening 14 arranged at an angle of approximately 34 degrees to the rear plate and parallel with the lower wall 11 of the web. The rear plate 5 on each side of the web is provided with thickened portions 15 provided with openings 16 and 17 through which passes the bolts 18 and 19 and 60 said bolts pass through vertical wall of the sill and leaving nuts 19 thereon whereby the anchor is tightly held in position.

The bands 20 encircle the tank 1 and leave their ends screw threaded at 21 and press 65 downwardly through the openings 14 in the web 9 of the anchor and leave nuts 22 screwed thereon to hold the bands tightly around the tank. Interposed between the nuts 22 and the lower face 23 of the web 9 70 are lock washers 24 which prevent the nuts from working loose caused by the jar of the car.

By this structure it will be seen that I have produced a durable anchor which can 85 be readily applied to the ordinary tank car now in use and which has the necessary strength yet producing an anchor in which the amount of metal is greatly reduced thus making a cheap and simple anchor.

90 The hollow web 9 is provided with an opening 25 through which extends the air pipe of the brake system, thus supporting the same and dispensing with separate brackets for supporting the pipe.

Having thus described my invention, what I claim and desire to secure by Letters Patent is:

1. A tank band anchor, comprising a body-portion formed of a plate having a 100 central outwardly extending central web having its lower end solid and curved outwardly and having an opening therethrough at an angle to the plate and through which passes the lower threaded end of the terminal and a nut on the threaded end below the web and preventing the longitudinal upward movement of the band.

105 2. A tank band anchor comprising a body-portion formed of a flat plate having 110

laterally turned upper and lower ends, a hollow central integral web carried by the plate and having an outwardly curved lower solid end having an opening therethrough at 5 an angle to the plate and through which the lower threaded end of the terminal of the band passes, the walls of the web having oppositely arranged openings extending at right angles to the other opening and

through which the air pipe of the brake system passes.

In testimony whereof I hereunto affix my signature in the presence of two witnesses.

GEORGE E. MITTINGER.

Witnesses.

G. W. JONSSON,
W. J. STUPPY.
